UNITED STATES PATENT OFFICE.

WILLIAM S. PROUDFIT, OF WALKER TOWNSHIP, KENT COUNTY, AND EDWARD F. GRAF, OF GRAND RAPIDS, MICHIGAN, ASSIGNEES TO PROUDFIT LOOSE LEAF CO., A CORPORATION OF MICHIGAN.

LOOSE-LEAF BINDER.

Application filed July 28, 1923. Serial No. 654,398.

Our invention relates to loose leaf binders in which thin, flat laterally resilient bands preferably made of highly tempered steel are attached to the covers with an intermediate leaf carrying portion spanning the space between the covers; the movement of the covers serving to flex the intermediate leaf holding portion so that the leaf body will be carried up from the back of the book when the covers are open, and oppositely into the back of the book when the covers are closed; and the objects of our invention are; first, to make a loose leaf binder in which the leaves will lie flat with a compact and easily manipulated means for detaching and adding leaves; second, to provide a clamping means on the covers for the edges of the leaf carrying bands; third, to positively guide the leaf carrying bands from the binding edge of the cover at a right angle thereto; fourth, to provide a passage along the cover outside the clamps for portions of plies of the leaf carrying bands not contained or embraced in the clamps; fifth, to make an economical and practical case to facilitate the assembling of the mechanical parts of the binder and to hold them in their operating position; sixth, to detachably connect a cross bar to the ends of the leaf carrying bands whereby they may all be adjusted simultaneously; seventh, to provide a lock for the clamping mechanism and other features to become apparent from the description to follow.

We attain these objects by the mechanism illustrated in the accompanying three sheets of drawings, in which Fig. 1 is a plan view of the inner face of one cover of a binder embodying our invention partly broken away; Fig. 2 is a cross sectional view of such binder in an open position; Fig. 3 is an enlarged plan view of a detachable connection for a cross bar at the extreme ends of the leaf carrying bands; Fig. 4 is a sectional view taken on line 4-4 of Fig. 3; Figs. 5, 6 and 7 are detail views of the parts shown in Figs. 3 and 4; Fig. 8 is a plan view of the clamps without a lock for holding the leaf carrying bands, enlarged, removed from the cover and showing the bands tightly clamped in position, partly broken away; Fig. 9 is a sectional view taken on line 9-9 of Fig. 8; Fig. 10 is a sectional view taken on line 10-10 of Fig.

1 showing both covers in an open position 55 and the leaf carrying bands locked in a position looped up between the binding edges of the covers in position to detach or add leaves; Fig. 11 is a sectional view taken on line 11-11 of Fig. 8, showing the 60 manner of fastening a cover plate to the base plate between which the mechanism is mounted; Fig. 12 is a detail perspective view of a clamp for the leaf carrying bands, detached; Fig. 13 is a plan view of the 65 leaf carrying bands clamping mechanism with a lock partly broken away to expose the key operated locking mechanism showing the same in an unlocked position; Fig. 14 is a similar view showing the key operated locking mechanism in a locked position; Fig. 15 is a sectional view taken on line 15-15 of Fig. 14; Figs. 16 and 17 are detail views of parts of the key locking mechanism shown in Figs. 13, 14 and 15 70 75 detached; Fig. 18 is a detail view of a portion of a cover plate showing the key hole; Fig. 19 is a side elevation of the key used to operate the lock; Fig. 20, is a perspective view showing the metal plate secured to 80 the fly leaf; Fig. 21, is a perspective view showing a filler plate used in connection with the lock, and Fig. 22, is a similar view showing a filler plate used without a lock. Similar reference characters refer to similar parts throughout the several views.

The covers 19 which may be constructed of the usual binder's board or any other suitable material, are hinged to the curved back 20 at 21 and have rigidly secured thereto the metal base plate 22, the up-turned edge of which at 23 forms the binding edge of the cover as clearly shown in Fig. 10. The hinge 21 is located a short distance back from the binding edge 23 to assist in 90 forcing the bound edges of the leaves upward into a curve as shown in Fig. 2. Metal plates 24, provided with slots 25' for the leaf carrying bands 25, see Figs. 2, 20 and 10, are preferably secured to the binding 95 edges of the fly leaves 23' adjacent to the covers to prevent abrasion of the leaves. The plates 24 may be secured to the fly leaves by folding the binding edge of the fly leaf around the plate and securing the 100 same on the opposite side thereof by means of spurs 24' provided on the edge of the plate 24.

The leaf carrying bands 25 are preferably made of thin, flat strips of spring steel, being stiff edgewise and laterally resilient and longitudinally nonextensible. One strip of 5 steel may be used for each band but we prefer to use for each band a plurality of these spring steel strips, one placed on top of the other, as this construction increases the strength of the bands and prevents them 10 from kinking more especially at the binding edges of the cover when the covers are opened and closed. It also provides a means of increasing the stiffness of these bands by adding more plies of spring steel strips 15 as the size of the leaf body increases. With this construction it is necessary to provide a means whereby these several plies of spring steel strips will adjust themselves longitudinally upon each other as the bands are flexed 20 back and forth with the movement of the covers. To provide this longitudinal adjustment we clamp only the ply next to the cover rigidly to the cover and provide a free passage over the clamps and a loose 25 connection to the cover for the other plies as hereinafter shown, thus permitting the different plies of the band 25 to move upon each other longitudinally.

The extremities of the bands 25 are 30 mounted on the inner surfaces of the covers with an intermediate portion for carrying the leaves lying between the covers. The extremities of the bands 25 attached to the covers 19 move in unison with the covers as 35 the binder is opened and closed, forcing the intermediate leaf carrying portion of the bands to assume a convex form when the covers are closed, parallel with the curved back 20, and when the covers are opened the 40 intermediate portion is carried in an opposite curve up and away from the back by the movement of the covers so that the binding edge of the leaf body when the covers are closed is convex in form and 45 when the covers are open it is concave in form. The bands 25 positively carry the leaf body 26 with them as they assume these different forms. This action permits the 50 usable portion of the leaves of the binder to lie flat when it is open for use. The sheets 26 are provided with suitable T-shaped notches in their binding edges to register with and receive the bands 25.

The bands 25 are slidably connected to 55 the covers 19 and to securely bind the leaf body of the binder when in normal position for use the bands are drawn up so that the binding edges of the covers press against the leaf body, and the bands are 60 then clamped to the cover as hereinafter shown. To remove or add sheets the binder is opened by unclamping the bands 25 when they may be drawn up into a loop between the cover by pulling on the fly leaf 65 23', and clamped in position as shown in

Fig. 10. When in this position the leaves 26 may be slid along on the bands 25 to any desired place on the bands and sheets may be withdrawn or added by means of the T-shaped notches in the leaves 26 in the usual 70 way.

The mechanism for clamping the bands 25 to the cover 19 (see Figs. 1, 2, 8, 9, 10 and 12), may be the same on both covers and comprises a pivoted cam 27 which, when 75 turned in one direction, will bring pressure against the edge of the band 25, and when turned in the opposite direction will release such pressure. The cam 27 may contact directly with the band 25 but we prefer to 80 loosely enclose the bands 25 in a pair of oppositely disposed embracing clamps 29 and to interpose between one member of the clamp 29 and the cam 27 a bearing shoe 28. The clamp 29 comprises two duplicate 85 oppositely disposed members 29^a each of which is folded at 29^b to embrace loosely one edge of the bottom ply of the band 25 and overlap the top and bottom surfaces of the ply for a major distance in width. The bottom 90 part 29^c of each member is provided with longitudinal end extensions 29^d bent down as at 29^e and adapted to be guided and held in place slidably by upturned lips 30 formed on the base plate 22.

The clamps 29 are placed on the plate 22 with their band engaging surfaces in a line at right angles to the binding edge of the covers 19, so that the clamps positively 100 force the intermediate leaf carrying portion of the bands 25 to depart from the covers 19 at right angles to the binding edges of said covers. This keeps the leaf body 26 in alignment and prevents it from sagging when the binder is stood on its end. 105

It is a great advantage in loose leaf binders of this type to provide a very thin and compact adjusting mechanism for the leaf holding members so as to permit the use of thin covers for the binder. We have therefore adapted the cam 27 to swing in a plane parallel with the surface of the cover 19, and to press the clamping members 29 against the edges of the bands 25, as this permits a very thin and flat construction of the mechanism. The overlapping portions of the clamps 29 prevent the band from buckling when pressure is brought against its edges. 110

While each cam 27 may be provided with 115 a handle or lever with which to turn it, we prefer to provide an intermediate pivoted gear 31 between each pair of cams 27 co-operating with different bands 25. The gear 31 is provided with an operating handle 32 and meshes with the segmental gears provided on the adjacent cams 27 so that a movement of handle 32 to the left 120 will move the two co-operating cams 27 in the proper direction for gripping two ad- 125

5 jacent bands 25. Where three bands 25 are used to hold the leaves as shown in the drawings the clamping mechanism may be positioned on each side of the center band, 10 the mechanism on one side being adapted to clamp one of the outside bands only by omitting the cam 27 and the bearing shoe 28 adjacent to the central band, and the other mechanism being adapted to clamp the remaining two bands. In this way the clamping mechanism may be adapted to operate any number of leaf holding bands. The rivets 33 are provided to secure the base plate 22 to the cover 19.

15 The cams 27 and pivoted gear 31 are assembled over the hollow cylindrical pivots 33' turned up from the base plate 22.

20 As clearly seen in Figs. 1, 2, 8, 9, 10, 11, 13, 14 and 15 a cover plate 34 is secured to the base plate 22 to cover the band clamping mechanism. The two opposite edges of the plate 34 are provided with a plurality of narrow extensions 35 and 36, see Fig. 11, which have their extremities extending 25 through registering slots provided therefor in the plate 22 and clamped on the under side of it to rigidly secure the two plates together.

25 A filler strip 37 is provided between the cams 27 and gear 31 and the cover plate 34 to hold the plate 34 spaced from the clamp 29 a sufficient distance to permit the free passage of one or more plies of the leaf carrying band 25. The filler 37 is retained 35 in position by having an integral lateral extension 38 which enters the hollow cylindrical pivots 33' of the cams 27 and the gear 31. The securing of the cover plate 34 into position retains the parts 27, 28, 31 and 37 in 40 their assembled positions. The cover plate 34 is provided with perforations 34' to register with one end of the clamps 29 to enable viewing the different plies of the leaf holding band 25 during the assembling process.

45 To enable the operator to adjust simultaneously all the leaf carrying bands 25, the ends of the bands are detachably connected to a bar 39, see Figs. 1 and 3 to 7, by means of a clip 40. At a proper distance 50 from their ends all the plies of the bands 25 are provided with a perforation 41 into which a small upward extending lug 42 provided on bar 39 projects. The bar 39 is provided with a slot 39' to receive the ends 55 of the bands 25, and to insure the lug 42 remaining in the perforations 41 the ends 43 of the U shaped clip 40 are also inserted into the slot 39' of bar 39 underlying the end 60 of the bands 25. The clip 40 has a downwardly extending lug 44 which enters the perforation 41 of the bands 25. The clip 40 is made of spring steel and to detach the same the part carrying the lug 44 is lifted by means of the upturned ears 44' to withdraw the lug 44 from the perforation 41

65 permitting the clip ends 43 to be withdrawn from the slot 39' in the bar 39, thus freeing the bands 25 so that they may be detached from the bar 39. It will be noted that the bar 39 connects the ends of all the bands 25 70 on one cover so that by manipulating bar 39 all of the bands 25 on the one cover 19 may be adjusted simultaneously. The perforations 41 are made larger than the lugs 42 and 44 to permit the several plies of the 75 bands 25 to move longitudinally upon each other.

80 When it is desired to lock the binder against manipulation by an unauthorized person, the locking mechanism illustrated in Figs. 13 to 19 is employed. The gear 31 is provided with two diametrically opposed upwardly extending lugs 45 arranged to extend into co-operating slots 46, provided in the floating ring 47 which is located within 85 a hole 48 provided therefor in the filler strip 37. One side of the ring 47 is provided with ratchet teeth 49 to co-operate with other ratchet teeth 50 on the inner periphery of the hole 48 in the filler strip 37. The ratchet teeth 49 and 50 are so arranged that when in engagement with one another the floating ring 47 and lever 32 are free to 90 be moved clockwise but are prevented from being moved non-clockwise as viewed in 95 Figs. 13, 14 and 17. A leaf spring 51 is mounted on the strip 37 to constantly tend to move the ring 47 in a direction to have the teeth 49 engage the teeth 50.

100 In Fig. 13 the ring 47 is shown as being held in a position against the tension of spring 51 with its teeth 49 disengaged from the teeth 50 so that the lock is in its unlocked condition, and the ring 47 and lever 32 are free to be moved in either direction to 105 the left or to the right. It is obvious that the ring 47 is carried either in one direction or the other by the movement of the lever 32, since the lugs 45 on gear 31 integral with lever 32 extend into slots 46 of the ring 47. 110 In Fig. 14 the ring 47 is shown as being forced into a position by a spring 51 with its teeth 49 engaging the teeth 50 so that the lock is in its locked condition and the lever 32 is free to be moved to the left but 115 is locked against movement to the right.

120 To move the ring 47 into its locked or unlocked position, a revolving cam disc 52 is employed which is pivoted about a pintle 53 pivotally mounted on the base plate 22, and projecting up through the keyhole 54 in plate 34 where it is provided with the usual key slot. The cam plate 52 is provided on its periphery with the cam surface 55 arranged to engage the extension 56 on the inner periphery of the ring 47, located diametrically opposite to the ratchet teeth 49, so that when the cam surface 55 is engaging the extension 56 the teeth 49 on ring 125 47 will be disengaged from the teeth 50 on

the strip 37. Thus it is clear that when the plate 52 is turned to have its cam surface 55 engage the extension 56 on ring 47, the parts will be in an unlocked position and when the plate 52 is turned to have its cam surface 55 out of engagement with the extension 56 on ring 47, the parts will be in an unlocked position. To turn the cam plate 52 from one position to the other, a key 57 is employed and the cam plate 52 is provided with suitable cut out portions to fit the key.

The pindle 53 is provided with a circumferential shoulder 53' to frictionally press the cam plate 52 against the cover plate 34, thereby preventing the cam plate 52 from being turned by any means except the key which fits.

Having thus fully described our invention what we claim as new and desire to secure by Letters Patent of the United States is:—

1. In a loose leaf binder a cover provided with a binding edge, a flat laterally resilient edgewise stiff leaf carrying band slidably connected to said cover, co-operating clamping members movably connected to said cover arranged to loosely embrace said leaf carrying band and means for pressing said clamping members against the edges of said leaf carrying band.

2. In a loose leaf binder, a cover provided with a binding edge, a flat laterally resilient edgewise stiff leaf carrying band slidably connected to said cover, co-operating clamping members movably connected to said cover arranged to loosely embrace said leaf carrying band, and means for pressing said clamping members against the edge of said leaf carrying band, comprising an eccentric lever connected to said cover and swinging in a plane parallel with the plane of said cover.

3. In a loose leaf binder a cover provided with a binding edge, a flat laterally resilient leaf carrying band slidably connected to said cover, co-operating clamping members movably connected to said cover arranged to loosely embrace said leaf carrying band, and means for pressing said clamping members against the edges of said leaf carrying band comprising a lever connected to said cover and swinging in a plane parallel with the plane of said cover and a bearing shoe interposed between said lever and one of said co-operating clamping members, said shoe being arranged to be eccentrically actuated by said lever.

4. In a loose leaf binder, a cover provided with a binding edge, a flat laterally resilient leaf carrying band slidably connected to said cover, co-operating clamping members movably connected to said cover arranged to loosely embrace said leaf carrying band, and means for pressing said clamping members against the edge of said leaf carrying band, comprising a gear hav-

ing an integral lever connected to said cover and moving in a plane parallel with the plane of said cover, a geared piece mounted eccentrically actuated by said lever, and a bearing shoe interposed between said geared piece and one of said co-operating clamping members, said shoe being adapted to be moved to bring pressure against the edge of said clamping member to clamp the leaf carrying band.

5. In a loose leaf binder, a cover provided with a binding edge, a flat laterally resilient edgewise stiff leaf carrying band extending at right angles from the binding edge of the cover slidably connected to said cover, co-operating clamping members movably connected to said cover arranged to loosely embrace said leaf carrying band and means for pressing one of said clamping members against the edge of said leaf carrying band, said means being positioned on said cover to hold said leaf carrying band firmly at a right angle to the binding edge of said cover.

6. In a loose leaf binder, a cover provided with a lower and upper plate with a free space between them, the edge of the lower plate constituting the binding edge of said cover and having a lip turned down therefrom, the upper plate being positioned a short distance back from the binding edge of the lower plate and having a lip turned up therefrom to register with the lip turned down from the lower plate, a leaf carrying band composed of a plurality of plies slidably connected to said cover extending between said lips into the free space between said plates, co-operating clamping members movably connected to said lower plate and arranged to loosely embrace one of said plies, means for pressing said clamping members against the edge of said ply and a free space between said clamping members and said upper plate arranged to permit of the passage of the other plies.

7. In a loose leaf binder, a cover provided with a lower and upper plate with a free space between them, leaf carrying bands and clamping mechanism therefor arranged between said plates, and means for fastening said plates together in position comprising orifices in one of said plates and lugs extending from the other of said plates to enter said orifices, said plates being adapted to hold the said clamping mechanism in assembled position.

8. In a loose leaf binder, a cover having a plate fastened thereto, a leaf carrying band and clamping means therefor carried on said plate, said clamping means comprising two co-operating bent members arranged to embrace the edges of said leaf carrying band and each of said members having a laterally outward extending portion, apertures in said plate adapted to re-

ceive said laterally extending portions and slidably engage them with the under side of said plate.

9. In a loose leaf binder, a cover, leaf carrying bands spaced apart and running along the inner surface of said cover, a bar at the ends of said bands and means for detachably fastening said bands to said bar comprising holes in the ends of said bands, upward turned lugs on said bar to enter said holes and an overlying detachable spring latching clip provided with a downward extending lug to enter said holes, and slots in said bar arranged to receive a portion of said clip and leaf carrying bands to retain them in position.

10. In a loose leaf binder, suitable covers, thin flat laterally springy edgewise stiff leaf carrying bands connecting the covers and adjustably connected to one of said covers and means on the cover for clamping the said strips edgewise.

11. In a loose leaf binder, suitable covers, thin flat springy leaf carrying bands connecting the covers and adjustably connected to one of said covers, clamps on the cover for clamping said strips edgewise and means at the clamps to prevent the strips from buckling when clamped.

12. In a loose leaf binder, suitable covers provided with metallic binding edges bent upwardly from the plane of the cover, a back hinged to the covers a short distance from the bent up binding edges, thin flat springy leaf carrying bands connecting the covers and adjustably connected to one of said covers and means on the cover for clamping the said bands edgewise, said hinges being so located with respect to the bent up binding edges that the portion of the leaf carrying bands between the binding edges of the covers will be forced downward into a curve when the covers are closed and will be forced upward into a curve when the covers are opened.

13. In a loose leaf binder, suitable covers, thin flat springy leaf carrying bands connecting the covers and adjustably connected to one of said covers, clamping means on the cover for clamping the said strips edgewise and a key operated lock for locking said clamping means against operation.

14. In a loose leaf binder, suitable covers, thin flat springy leaf carrying bands connecting the covers and adjustably connected to one of said covers, clamping means on the cover for clamping said bands edgewise in their adjusted position, means associated with said clamping means to prevent the bands from buckling when clamped and a key operated lock for locking said clamping means against operation.

15. In a loose leaf binder, suitable covers provided with metallic binding edges bent upwardly from the plane of the cover, a

back hinged to the covers a short distance from the bent up binding edges, thin flat springy leaf carrying bands connecting the covers and adjustably connected to one of said covers, clamping means on the cover for clamping the said bands edgewise, a key operated lock on the cover for locking said clamping means and said hinges being so located with respect to the bent up binding edges that the portion of the leaf carrying bands between the binding edges of the covers will be forced downward into a curve when the covers are closed and will be forced upward into a curve when the covers are opened.

16. In a loose leaf binder, suitable covers, thin flat springy leaf carrying bands connecting the covers and adjustably connected to one of said covers, means on the cover for clamping the said strips edgewise comprising a pivoted swinging lever and a key operated lock on the cover for locking said lever against movement in one direction.

17. In a loose leaf binder, suitable covers, thin flat springy leaf carrying bands connecting the covers and adjustably connected to one of said covers, clamping means on the cover for clamping said bands edgewise in their adjusted position comprising a pivoted swinging lever, a key operated lock on the cover for locking said lever against movement in one direction and means associated with the clamping means to prevent the bands from buckling when clamped.

18. In a loose leaf binder, suitable covers provided with metallic binding edges bent upwardly from the plane of the cover, a back hinged to the covers a short distance from the bent up binding edges, thin flat springy leaf carrying bands connecting the covers and adjustably connected to one of said covers, clamping means on the cover for clamping the said band edgewise comprising a pivoted swinging lever, a key operated lock on the cover for locking said lever against movement in one direction and said hinges being so located with respect to the bent up binding edges that the portion of the leaf carrying bands between the binding edges of the covers will be forced downward into a curve when the covers are closed and will be forced upward into a curve when the covers are opened.

19. In a loose leaf binder, covers, thin flat springy leaf carrying bands connecting the covers and adjustably connected to one of said covers, means for clamping the said bands edgewise and to prevent the bands from buckling when clamped comprising a U shaped clamp member mounted on the cover to move laterally but held against movement longitudinally and means for moving the clamp member tightly against the edge of the band.

20. In a loose leaf binder, covers, thin flat

springy leaf carrying bands connecting the covers and adjustably connected to one of said covers, means mounted on the cover for clamping said band edgewise and to prevent it from buckling when clamped comprising a fixed U shaped clamp member and a movable U shaped clamp member mounted to have lateral movement but held against longitudinal movement and means comprising a pivoted cam for moving said clamp member tightly against the edge of said strip.

21. In a loose leaf binder, covers, a thin flat springy leaf carrying band connecting the covers and adjustably connected to one of said covers, means mounted on the cover to clamp said band edgewise and to prevent it from buckling when clamped comprising a U shaped clamp member movable later-

ally but held against movement longitudinally, means comprising a pivoted lever for forcing said clamp member against the edge of the strip and a key operated lock for locking said lever against movement.

22. In a loose leaf binder, covers, thin flat laterally springy edgewise stiff leaf carrying bands connecting the covers and adjustably connected to one of said covers, and means on the cover for clamping the bands edgewise and positively forcing the bands to lie in a position extending from the cover at right angles to the binding edge of the cover.

In testimony whereof we have signed our names to this specification this 15th day of May, 1923, at Grand Rapids, Michigan.

EDWARD F. GRAF.
WILLIAM S. PROUDFIT.
